UNITED STATES PATENT OFFICE

HARRY SWINGLEHURST, OF ORANGE, NEW JERSEY, ASSIGNOR TO SCOTT AND WILLIAMS, INC., OF NEW YORK, N. Y., A CORPORATION OF MASSACHUSETTS

DIAL AND CYLINDER INTERLOCKING MECHANISM

Application filed October 7, 1929. Serial No. 398,018.

This invention has to do with circular knitting machines of the sort having a needle dial and a needle cylinder with devices, generally termed "dogs", which lock the dial and cylinder against relative rotation in one direction but at the same time permit the fabric to pass down between them under the influence of the fabric take-up. I provide a number of radially movable dogs on the under side of the dial and a number of fixed dogs on the cylinder co-operating therewith. Butts on the inner ends of the movable dogs rest in a cam track provided with successive retracting portions which are so related that some of the co-operating pairs of dogs are separated at one time and others at another time. By reason of this, the relation of interlock between the dial and the cylinder is maintained at all times but the fabric is enabled to be drawn down without dragging on the dogs.

The underlying thought here is to have a radially movable dog and a fixed dog and to provide one dog with a beveled face, that is, a face presented in such direction that it may engage the other dog to resist relative rotation yet so inclined from the radial that upon relative radial movement between the dogs a quick separation is effected. The engaging face of the other dog may be correspondingly beveled but preferably is curved.

In the drawings herewith, Figure 1 shows a part of the knitting head of a circular machine with a part of the dial broken away to show the interlocking dogs and the cam track. The knitting instrumentalities and their associated parts are omitted.

Figure 2 is a perspective view of the movable dog and the parts which support it for a radial movement and hold it on the dial. These parts are shown assembled and inverted from the position they occupy when on the dial.

Figure 3 is a view in section on the line 3—3 in Figure 2 but it shows the parts in their normal position, not inverted as in Figure 2.

The needle dial and the needle cylinder may be mounted and driven in any suitable manner or they may be fixed and the cams for operating the needles may be rotated.

Here however there is shown a machine in which the needle cylinder 10 is fixed as is the dial 11 which is freely mounted on the central spindle but is held from rotation therewith by means of the interlocking dogs. The cylinder cam ring 10^a is rotated. There are four fixed dogs 12 equally spaced about and secured to the inner face of the cylinder at its upper rim. Each has a face 13 that is vertical but is inclined away from a radial plane, its inclination being such however that it is more nearly radial than tangential.

Each co-operating movable dog consists of a shank 14 with a head 15 at its outer end and a butt 16 at its inner end. The head has a downward extension 17 to correspond to the height of the inclined vertical face 13 of the co-operating fixed dog and has also a nose 18 offset toward the fixed dog. The surface 19 of this nose is curved and thus it has substantially a line contact with the flat face 13 of the fixed dog. The result of this is that upon retraction of the movable dogs on a radial or substantially radial line, there is no appreciable sliding of the one dog on the other but a quick separation occurs creating a space between the co-operating parts of the two dogs. When the movable dog is unretracted, there is an engagement between these parts such that forces are transmitted between the cylinder dog and the dial dog along a practically tangential line so that the major component of the force exerted is effective in resisting a turning of the dial.

The shank of the movable dog is rectangular in cross section and is received in a similarly shaped slot 20 in a block 21 that is adjustably mounted on a plate 22 secured to the under side of the dial 11. A sidewise adjustment of the block is made possible by the fact that the screws 23 which hold the block and the plate to the dial extend through enlarged holes 24 in the side flanges 25 of the block. A pair of pins 26 are mounted on either side of the plate 22 and extend through slots 27 in the side flanges of the block. These pins carry adjusting screws 28 that bear against the side faces of the main part of the block, thus determining between them the location of the block on the plate within the limits permitted.

by the enlarged holes 24 and the slots 27. The cap plate 29 holds the shank of the dog in its slot 20 in the block 21.

The butt at the inner end of the shank of each dog is a roller disc and rests in a shallow groove 30 formed in a ring that is supported on a bracket 31. The bracket rotates with the central spindle 35 in the direction indicated by the arrow in Figure 1. The hub 32 to which the dial plate 11 is secured rests on a roller bearing (not shown) on a collar which turns with the spindle. At six equally spaced points about the groove 30 are retracting cams 33 and opposite each one is a concavity 34 in the inner face of the groove to permit the roller 16 to be withdrawn by the cam. The width of the groove 30 is greater than that of the roller butt 16 to facilitate the assembly, the cam ring being put on from beneath after the dial plate is in place and then adjusted until the rollers 16 rest properly in the groove. The retracting cams are so related to one another that only two, and these diametrically opposite, dogs are retracted at a time. The action of the retracting cam is to move the shank of the dial dog radially inward, thus separating the nose 18 at its outer end from the inclined or beveled face 13 of the associated fixed dog to permit the fabric to slide between the two dogs. The sidewise adjustment of the block makes it possible to fix with nicety the line of contact between the nose of the movable dog and the beveled face of the fixed dog.

35 The underlying thought of my invention may be used with various arrangements of the parts involved and I therefore wish to include within the scope of the protection afforded by a patent all variations from the form shown here which may come within the fair range of the following claims.

I claim—

1. Mechanism for interlocking a needle dial and a needle cylinder in a circular knitting machine, comprising a radially movable dog on one of said elements and a fixed dog on the other, one of said dogs having a face inclined away from the radial, in combination with means for reciprocating the radially moving dog at each revolution.
- 45 2. Mechanism for interlocking a needle dial and a needle cylinder in a circular knitting machine comprising a radially movable dog on the dial and a fixed dog on the cylinder, said fixed dog having a face inclined away from the radial and said movable dog having a head with a curved surface adapted to engage said face, in combination with means for reciprocating the radially moving dog at each revolution.
- 55 3. In a circular knitting machine, a needle dial and a needle cylinder with interlocking mechanism comprising a radially movable dog and a fixed dog in such engagement as to resist relative rotation in one direction, the

engaging face of one dog being beveled, in combination with means for reciprocating the radially moving dog at each revolution.

4. In a circular knitting machine, a needle dial and a needle cylinder with interlocking mechanism comprising a radially movable dog and a fixed dog in such engagement as to resist relative rotation in one direction, the engaging face of one dog being beveled and that of the other being curved, in combination with means for reciprocating the radially moving dog at each revolution.

70 5. In a circular knitting machine, a needle dial and a needle cylinder, interlocking mechanism therefor comprising a radially movable dog on the dial, a support for the movable dog and a fixed dog on the cylinder, and means for adjusting the support for the movable dog sidewise on the dial.

75 6. In a circular knitting machine, a needle dial and a needle cylinder, interlocking mechanism therefor comprising a fixed dog on the cylinder and a radially movable dog on the dial, said dog having a downwardly extending butt at its inner end, in combination with a circular groove provided with cams for actuating the dogs on the dial, said groove being wider than said butts.

80 In testimony whereof I have signed my name to this specification.
